JOHN F. O'CONNOR, OF CHICAGO, ILLINOIS, ASSIGNOR TO WILLIAM H. MINER, OF CHAZY, NEW YORK.

ROLLER SIDE BEARING.

1,290,323.

Specification of Letters Patent

Patented Jan. 7, 1919.

Application filed March 4, 1918. Serial No. 220,234.

To all whom it may concern:

Be it known that I, JOHN F. O'CONNOR, a citizen of the United States, residing at Chicago, in the county of Cook and State of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

As is well known, in the operation of railway cars there is considerable wear on 15 the center bearing plates of the body and truck bolsters so that the relative positions of the body and truck bolsters vary while the car is in service. To compensate for this wear on the center plates, it is sometimes customary to introduce shims from 20 time to time.

Due to the wear of the parts and introduction of shims, as above described, it has been customary to make the anti-friction 25 roller side bearings adjustable to compensate for the variations occurring in service. This necessitates a more or less expensive side bearing due to the adjustable feature.

The object of my invention is to provide 30 a novel arrangement of roller side bearings for railway cars and wherein the necessity for any adjustment is avoided in compensating for wear at the center plates, above referred to.

In the drawing forming a part of this 35 specification, Figure 1 is a transverse, sectional view of a portion of a railway car showing my improvements in connection therewith. Fig. 2 is a sectional view, taken 40 substantially on the line 2—2 of Fig. 1.

In said drawing, 10 denotes a portion of a body bolster of a car to which is secured a center bearing plate 11. Said center bearing plate 11 of the body bolster co-operates 45 with a corresponding center bearing plate 12 carried by the truck bolster 13, said center bearing plates 11 and 12 being suitably recessed, as indicated at 14 and 15, to accommodate the usual center or king-pin for 50 pivotally connecting the bolsters.

In carrying out my invention, I have shown the anti-friction roller proper as mounted on the body bolster, but it will be obvious to those skilled in the art that the 55 position of the parts may be reversed with-

out departing from the spirit of the invention. As shown, on each side of the king-pin 1 I have mounted an anti-friction roller 16 in a bracket or retainer casting 17, the latter being riveted or otherwise suitably secured to the body bolster 10. As clearly appears from the drawing, the rollers 16 are rotatable about vertical axes, which is a departure from the usual custom. To co-operate with the rollers 16 the truck bolster 60 13 is provided at either end thereof with upstanding built-up sections 18 to the tops of which are secured bearing plates or castings 19. Each of said bearing plates 19 is provided on its inner face with a vertically 65 extending bearing surface or wall 20 adapted to co-operate with the corresponding anti-friction roller 16. Said surface or wall 20 is curved on a radius corresponding to the distance to the center or king-pin so that, 70 as the truck swivels with respect to the car body, the anti-friction roller 16 will always remain in contact with the bearing wall 20. The height of the bearing surfaces or walls 20 is preferably made higher than the width 75 of the anti-friction rollers 16 so that the latter may be moved up or down with respect to the bearing walls 20 and yet at all times remain in contact with the latter.

From the preceding description, it will 80 be seen that there will always be contact between the anti-friction rollers and the bearing plates, regardless of the wear on the center plates 11 and 12 and even when shims are introduced therebetween inasmuch as 85 the contact between the rollers and the bearing plates is independent of their vertical relation within, of course, the limits provided for in the structure. The arrangement is of great simplicity since it employs 90 merely the three necessary elements, a bearing plate, an anti-friction roller, and a supporting casting for the roller; and the bearings will effectively prevent undue swaying 95 of the car body relatively to the trucks as the cars pass from a straight section of track to a curved section or vice versa.

I claim:

1. In a railway car having body and truck bolsters, the combination with a pair of 105 diametrically disposed anti-friction rollers mounted on one of said bolsters and each rotatable about a vertical axis; of a pair of separated co-operating bearing plates carried by the other bolster, each of said bear- 110

ing plates having its bearing surface extending vertically and engageable with said roller.

2. In a railway car having body and truck bolsters, the combination with a pair of diametrically disposed anti-friction rollers carried by one of said bolsters and each rotatable about a vertical axis; of a pair of separated bearing plates carried by the 10 other of said bolsters, each of said bearing

plates having the wearing surface thereof extending vertically and curved on a radius of a length corresponding to the distance from the axis of the pivotal connection of the bolsters and with its center coinciding 15 with said axis.

In witness that I claim the foregoing I have hereunto subscribed my name this 16th day of Feb., 1918,

JOHN F. O'CONNOR.
